UNITED STATES PATENT OFFICE

2,084,993

MACHINE KNIFE

Charles E. G. Aff, Jamaica, N. Y.

Application March 22, 1935, Serial No. 12,423

4 Claims. (Cl. 164—58)

This invention relates to improvements in machine knives, particularly for use in cutting paper and similar sheet stock, and has for a principal object the provision of an extension which may 5 be applied to the knife after it has become too short for use due to repeated sharpenings, thereby increasing the life of the knife.

In machine knives the knife bars, to which the knives are secured, each have a surface against 10 which the back edge of the knife members, and another surface at right angles to said first surface, and against which the face of the knife contacts when the knife is secured thereto. The knife is secured to the knife bar by means of 15 bolts passing through the knife bar and engaging threaded holes in the knife. Usually the surface in the vicinity of the bolt holes in the knife bar is under-cut or relieved so that the knife may be tightly clamped against the knife 20 bar in parallel relation to the surface of the knife bar.

The knife, due to repeated grindings, eventually becomes too short for use. As the knife still 25 contains good cutting steel, it is poor economy to throw it away when it reaches this state. In devices of the prior art the life of these knives has been extended in two ways: (a) by providing the knife bar with screws bearing against the back or blunt edge of the knife; and (b) by 30 screwing or pinning an extension on to the back or blunt edge of the knife.

The first of these methods has the distinct disadvantage in that when the knife is bolted to the knife bar, and the bolts are tightened, the blunt 35 edge of the knife is forced into the undercut portion of the surface of the knife bar with the result that the knife is "cocked". The second of these methods gives a similar result due to the fact that strains, due to the clamping action of 40 the bolts, are imparted to the screws or pins and the blunt edge of the knife is forced into the under-cut portion of the knife bar and out of parallel relation to the surface of the knife bar. This second method is shown and described in 45 Patent No. 596,530 issued on January 4th, 1898 to Thomas F. McCoy.

A further object of the present invention is the provision of an extension bar so formed that it may be easily applied to my new and improved 50 machine knife after the latter has become too short due to repeated sharpenings, and securing the knife and the extension bar together in such relation that regardless of the position of the under-cut portion of the knife bar about the bolt holes in the latter, the knife and extension

assembly is practically as rigid as the knife was originally and will maintain its perfect perpendicular position when clamped in parallel relation to the knife bar.

Machine knives like any other articles made of tempered steels have various internal stresses and strains. As the knives are ground away due to repeated sharpenings these stresses effect warping in the knife thereby making it more or less difficult to apply an extension bar thereto 5 or to remove the same therefrom, and due to the small amount of space between the knife bar and the paper clamping member, it is difficult to insert a warped blade therebetween.

Another object of the invention is the provision 10 of a novel method of applying extension bars to machine knives and/or removing extension bars therefrom, wherein an extension bar, when applied to the knife, becomes, in effect, a knife 15 holder.

Other objects and advantages will become apparent to those skilled in the art.

Referring to the drawing:

Figure 1 is an elevation of a knife constructed 20 according to a preferred form of the invention and which, due to repeated grindings, is too short to be used in a machine;

Figure 2 is an elevation of a portion of an extension bar adapted to be used with the knife shown in Figure 1;

Figure 3 is a sectional elevation of the knife 30 taken along the line 3—3 of Figure 1;

Figure 4 is a sectional elevation of the extension bar taken along the line 4—4 in Figure 2;

Figure 5 is a sectional elevation of the knife 35 taken along the line 5—5 of Figure 1;

Figure 6 is a sectional elevation of the extension bar taken along the line 6—6 of Figure 2;

Figure 7 is a fragmentary view of an assembly 40 of the knife shown in Figure 1 and the extension bar shown in Figure 2;

Figure 8 is a sectional elevation of the knife and extension bar assembly taken along the line 45 8—8 of Figure 7;

Figure 9 is a sectional elevation of the assembly taken along the line 9—9 of Figure 7;

Figure 10 is a side elevation of a threaded bushing which is included between the knife and the knife bar thereby providing a further means 50 for clamping the assembly to the knife bar of a machine;

Figure 11 is an isometric view of the device shown in Figure 10;

Figure 12 is a sectional elevation of a typi- 55

cal knife bar with a machine knife secured thereto; and

Figure 13 shows a jig for assembling the knife and the extension bar.

5 The typical knife bar of a machine is shown in Figure 12 and designated by the numeral 20. This knife bar has a surface 21 which moves in a parallel line when the knife bar, in its normal position in the machine, is actuated. The knife bar also has a surface 22 which is substantially at 10 right angles to the surface 21.

15 The knife bar is provided with a plurality of bolt holes, one of which is shown and designated by the numeral 23. The hole 23 has a counter-bored portion 24 which is of sufficient size to provide clearance for the bolts, one of which is designated by the numeral 25, and washers 26.

20 The knife, generally designated by the numeral 27, is usually made of wrought iron or lower 25 grades of steel and has applied thereto by welding or any other suitable manner a portion 28 of high grade steel which is tempered and capable of maintaining a sharp cutting edge. The knife also has a beveled portion 29 forming a surface 25 face along which grinding is effected.

30 The front surface 30 of the knife is ground true and is the surface which engages and aligns precisely with the surface 21 of the knife bar. In order that this alignment may be maintained 35 as precisely as possible it is customary with most of the machine manufacturers to under-cut the surface of the knife bar along a longitudinal zone about the bolt hole 23 thereby forming a depression 31 in the surface 21 of the knife bar.

35 The blunt or back edge of the knife (the edge opposite to the cutting edge) at its junction with the surface 30 is provided with a chamfer 32 thereby eliminating a square corner, forming a distinct bevelled edge, making it possible to force 40 the knife in under the bottom edge of the knife bar 20 when the knife has become warped as described above, and further making it possible for the surface 30 to member up with the surface 21 and the blunt edge of the knife to member up 45 with the surface 22 without distortion.

50 A plurality of tapped holes 33, 34, and 35 and similar holes, one set of which is designated by the numerals 33a, 34a, and 35a, are provided in the knife, to be engaged by clamping bolts such as that designated by the numeral 25. As the 55 knife grows shorter due to repeated sharpenings they may be lowered in the knife bar so that the bolts 25 which engage normally the holes 33-33a are allowed to engage the holes 34-34a. In this position the portion of the knife extending below the knife bar is lengthened.

55 As the knife becomes still shorter it may be lowered to the point where the bolts 25 engage the holes 35-35a. At this stage the chamfered 60 corner 32 of the knife 27 is pulled into the depression 31 by the bolts 25 when they are tightened, thereby "cocking" the knife out of parallel relative to the surface 21. This causes the knife to mutilate the work and to strike other portions 65 of the machine adjacent to the knife, resulting in scarring said portions and dulling the knife.

70 When the knife is so short that it is necessary to use the holes 35-35a the effect immediately above described is eliminated by the addition to the knife of an extension bar such as that shown in Figure 2 and designated by the numeral 36. This extension bar is of substantially the same thickness as that of the knife. The extension bar is provided with a plurality of sector shaped 75 tongues each having a hole 38 formed therein.

The number of these tongues used varies with the length of the knife.

The knife 27a is provided with sector shaped or curvilinear depressions 39 which are similar in shape to the tongues 37. These depressions are of such width that the tongues 37 form a press fit therein.

10 In the portion of the knife in which the depression 39 is formed, a tapped hole 40 is provided in such position that when the tongue 37 is in position in the depression 39 this tapped hole is in line with the hole 38. The knife is also provided with a hole 41 concentric with the hole 40 and forming a fit with a screw head such as the screw 42 shown in Figure 8. Figure 8 shows 15 the knife and knife bar assembled with the tongue 37 in position in the depression 39 and a screw 42 retaining them in this relation.

20 When assembled the head of the screw 42 should be a few thousandths of an inch below 25 the surface 30a of the knife and forms a dowel fitting both the hole 38 in the tongue 37 and the hole 41 in the knife.

25 The extension bar 36 has a plurality of semi-circular depressions 43 milled therein and a plurality of other semi-circular depressions 44 in stepped relation to and concentric with the depressions 43. Matching these semi-circular depressions, when the tongue 37 is in position in the depression 39, is a series of semi-circular depressions 45 in the knife and another series of semi-circular depressions 46 matching the depressions 44 forming a circular stepped hole in the assembly. 30

35 A hole 47 is formed in the semi-circular depressions 43 at right angles to the axis thereof and is preferably centrally located in said depressions. A similar hole 48 is formed in the surface of the depressions 45 in such manner that when the extension bar and knife are assembled 40 the holes 47 and 48 are oppositely disposed.

45 A bushing 49 is provided with a threaded hole 50 of the same pitch and number of threads as that of the bolt 25. The outside of the bushing has a portion 51 of the same thickness and diameter of that of the depressions 44 and 46. The bushing 49 also has a reduced portion 52 of a diameter and length equal to the depressions 43 and 45. The bushing 49 is provided with pins 53 and 54 which engage the holes 47 and 48 respectively when the knife and the extension bar are assembled as shown in Figure 9.

50 When assembled in the manner just described, the threaded hole 50 is substantially in line with the hole 34a in the knife.

55 The extension is also provided with a plurality of tapped holes 55 the purpose of which will presently be described.

60 When the extension 36 is applied to a worn knife 27a its length is increased so that the upper hole 35 and the new added hole 50 may be used for lowering the knife as it is ground away by repeated sharpenings.

65 As pointed out above, stresses and strains within the metal forming the knife are relieved to some extent by repeated grindings and resulting in warping the knife itself. This being the case the depressions 39 formed in the knife, due to this warpage, will not all be in line with each other and with the tongues 37 carried by the extension bar 36.

70 To overcome this difficulty a fixture such as is illustrated in Figure 13 was devised for applying extension bars to and/or removing them from knives.

A pair of old knives 56 and 57 are utilized. A plurality of members, generally designated by the numeral 58, are secured to these knives.

The members 58 each consist of a block 59 having formed therein a slot 60 in which a metallic strip 61 is mounted at right angles to the block. The metallic strip 61 is secured to the block 59 by means of screws 62. A screw 63, having threads matching the threaded hole 33b in the knife 56, secures the member 58 to the knife 56 with the metallic strip 61 resting on the blunt end of the knife 56. Before the member 58 is secured to the knife 56 the shank 66 of an eye bolt 64 is screwed into a threaded hole 67 formed in the metallic strip 61. When the member 58 is secured to the knife as above described a screw 65 passing through the eye of the bolt 64 is utilized for securing the head of the eye bolt to the knife 57. While the screw 65 is being tightened the metallic strip 61 is firmly held down against the blunt edge of the knife 57.

The block 59 has formed therein a clearance hole 69 which is of suitable diameter to form a clearance for a screw 70. The screw 70 is of such diameter and has threads of a pitch matching the holes 55 in the extension bar 36. The block 59 is also provided with a second hole 71 which is tapped to fit the threads of the screw 10. The screw 70 is also provided with a wing nut.

Normally the nuts 68 are not screwed down onto the metallic strip 61. They are not placed on the threaded shank 66 of the eye bolts until after the knife 27a is positioned on the fixture as shown in Figure 13.

A plurality of assemblies or members 58 (the number varying in accordance with the length of the knife) is applied to the old knives 56 and 57. The knife 27a to which the extension bar 36 is to be applied is placed upon the assembly 56-57-58 with the threaded tongues 66 of the bolts 64 preferably extending through the holes 34-34a after which the nuts 68 are applied and tightened down thereby clamping the old knife 57, the metallic strips 61 and the knife 27a rigidly together. As all of the metallic strips 61 are of the same thickness and as the assemblies 58, of which the strips 61 are members, are positioned near together along the surface of the old knives 56 and 57 the warpage in the knife 27a is compensated for.

To apply an extension bar 36 to the knife 27a screws 70 are screwed into the holes 71 in the various blocks 59 and these screws are turned until they all member up against the edge of the extension bar 36 which had previously been placed in position across the metallic strip 61 with the tongues 37 in cooperative relation to the depressions 39 in the knife.

A bushing 49 is placed in position in each depression 45-46 or 43-44 with the pin 53 or 54 in line respectively with the hole 48 or the hole 47. When this has been done the screws 70 may be rotated or turned to force the tongues 37 of the extension bar 36 into engagement with the depressions 39 in the knife. It has been found preferable to progressively advance each screw, bearing along the length of the extension bar, so that the extension bar 36 is moved forward toward the knife in as near a parallel manner as possible.

When the operation has reached the stage where the flat surfaces of the extension bar are in contact with the blunt edge 22a of the knife the tongues 37 are completely within the depressions 39 at which time the holes 38 and 40 coin-

cide with each other and the depressions 43-44 and 45-46 completely embrace the bushing 49 with the pin 54 in the hole 48 and the pin 53 in the hole 47 after which the screws 42 may be inserted in the holes 41 and screwed into the holes 40 thereby securing the knife and the extension bar together and forming a rigid structure. The nuts 68 may then be removed and the knife-extension bar assembly is ready to be applied to the machine.

This invention contemplates the production of knives having, in addition to the holes 33-34-35 therein, depressions 39 formed therein and depressions 45-46 and the holes 40-41 and 48 formed therein so that no machine work is necessary on the premises of the customers to apply an extension bar to a knife.

A single extension bar may be used over and over from time to time on various worn knives.

To remove an extension bar from a knife the knife-extension bar assembly is placed on the fixture made by the old knives 56 and 57 and members 58 and the nuts 68 are screwed down to tightly clamp the assembly on to the fixture. The screws 70 are then inserted into the holes 69 and screwed into the tapped holes 55 in the extension bar 36. The screws 42 are then removed from the knife and extension bar assembly after which the wing nuts 72 may be turned to pull the extension bar 36 from the knife 27a thereby making the extension bar 36 available to be applied to other worn knives.

Due to the rigid structure formed by combining the knife and the extension bar in the manner shown and described herein, as far as clamping the knife to the knife bar 20 of the machine, this assembly is substantially as rigid as a new knife would be and will give the same result as a new knife.

The depression 31 in the surface 21 of the knife bar cannot distort the new and improved assembly knife and extension bar.

In some of the machines employing knives, the knife bar is provided with a series of holes, one of which is indicated in dotted lines in Figure 12 and designated by the numeral 74. When the knife becomes too short to use the holes 33-33a the knife is removed from the knife bar and a rectangular strip is affixed to the knife bar by means of screws passing through the holes 74. This strip is of such width that when the knife is positioned against it it may be bolted to the knife bar by bolts engaging the holes 34-34a. When the knife becomes too short to utilize the holes 34-34a the knife is removed from the knife bar and a wider strip is substituted for the strip just described and this latter strip is of such width that when the blunt edge of the knife members up against it the bolts in the knife bar will engage the holes 35-35a. In many cases the difficulty encountered is that the chamfered corner 32 in a knife enters the depression 31 in the knife bar and when pressure is applied to the knife by means of the bolts 25 the knife is "cocked" and does not function in the machine as it should.

Extending the knife by this method is only a make-shift and cannot approximate the results obtained by the new and improved knife-extension bar assembly described herein which forms a rigid structure and in which the surface 73 of the extension bar positively members up with the surface 22 of the knife bar and due to the rigidity of the structure the position of the knife is not distorted due to the presence of the depression 31 in the knife bar.

Although a preferred embodiment of the invention is herein shown and described it is obvious that many modifications may be made by those skilled in the art without departing from the spirit of the invention as defined in the following claims.

What is claimed is:

1. A machine knife adapted to be secured to a movable part of said machine, a plurality of 10 mortises formed within said knife and communicating with one plane surface thereof, an extension bar having a plurality of tenons extending from one surface thereof adapted to be contained in said mortises when the bar is applied to the 15 knife with said surfaces in contact with each other, tapped holes formed in said knife each communicating with one of said mortises, clearance holes formed in said knife each concentric with one of said tapped holes, a clearance hole 20 formed in each of said tenons concentric with and parallel to said first clearance holes when said tenons are contained in said mortises, and screws 25 extending through said clearance holes and into said tapped holes for securing the knife and the extension bar together to form a rigid structure.

2. A machine knife adapted to be secured to a movable part of said machine, a plurality of keyways of the "Woodruff" type formed in said knife and communicating with one plane surface thereof, an extension bar having a plurality of keys formed integral therewith and extending from one surface thereof, said keys being adapted to be contained in said keyways when the bar is applied to the knife with said surfaces in contact 35 with each other, tapped holes formed in said knife each being transverse to and communicating with one of said keyways, clearance holes formed in said knife each being concentric with one of said tapped holes, a clearance hole formed 40 in each of said keys transverse thereto, concentric with and parallel to said first clearance holes when said knife and said extension bar are assembled with said keys positioned in said keyways, and screws having heads forming dowels fitting

both said clearance holes and having shanks threaded to match said tapped holes for securing the knife and the extension bar together to form a rigid structure.

3. In combination, a knife, an extension bar 5 for extending the use of said knife when the latter becomes too short for use due to repeated grindings, means forming a plurality of curvilinear grooves disposed along substantially the longitudinal axis of the knife and terminating in the 10 upper surface thereof, a plurality of curvilinear tongues formed integral with said bar along one surface thereof and adapted to be contained entirely within said grooves in the mass of the knife for holding the knife in rigid relation to said extension bar, and screw means cutting at least two surfaces of said knife within the zone of each of said curvilinear grooves and passing transversely through said tongues for retaining the knife and the extension bar in fixed relation to 15 each other.

4. As an article of manufacture, a machine knife having a series of tapped holes formed therein for attachment to a movable member of a machine, said knife having a cutting edge, two 25 parallel faces and a blunt edge opposite to said cutting edge and at right angles to said parallel faces, means forming a plurality of semi-circular grooves within the body of said knife and communicating with said blunt edge, holes formed in 30 said knife and extending from one of said faces to the other of said faces through said grooves and having a portion of their lengths threaded, an extension bar having semi-circular tongues adapted to fit said grooves, means forming a hole 35 passing transversely through each of said tongues, said holes being so positioned that they are concentric with said first holes when the knife and the extension bar are assembled with said tongues positioned within said grooves, and screws having shanks fitting said holes and threaded portions fitting the threaded lengths of said holes.

CHARLES E. G. AFF.
